UNITED STATES PATENT OFFICE.

NICHOLAS FEINEN, OF BUFFALO, NEW YORK.

TIME SWITCH.

Application filed June 25, 1921. Serial No. 480,412.

This invention relates to improvements in time switches, the general object of the invention being to provide clock means for moving the switch to its open position and 5 also to provide manually operated means for actuating the switch.

Another object of the invention is to provide a dial and a cooperating finger which is connected with the arbor of the clock 10 mechanism with means for connecting said arbor with the switch and with a setting disc.

A further object of the invention is to provide a shaft which passes through the 15 hollow arbor and carries the switch blade and a finger disc.

A still further object of the invention is to provide a casing for the clock mechanism with insulated blocks at the rear thereof 20 for containing the switch parts and into which the arbor and switch shaft extend.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of the invention.

Figure 2 is a longitudinal sectional view.

Figure 3 is a view of the rear face of the inner block showing the parts of the snap switch.

Figure 4 is a view of the opposite face 40 of this block showing the time switch.

Figure 5 is a view similar to Figure 3 with the switch blade arranged in inoperative position.

Figure 6 illustrates perspective views of 45 some of the parts of the switch.

In these views 1 indicates the casing for enclosing the clock mechanism which is indicated generally at 2. The hollow shaft or arbor 3, to which the spring 2' of the 50 clock mechanism is connected, extends entirely through the casing with its ends projecting therefrom. The indicator finger 4 is suitably connected with the front projecting end of said arbor. This end of the 55 arbor is provided with the notches which are adapted to receive the projections 6 of

the setting disc 7 so that the spring can be wound and the finger adjusted to its desired position on the dial 8 on the front face of the casing. The rear projecting end 60 of the shaft or arbor has secured thereto the ring 9 which is provided with the projections 10 for engaging notches 11 in the switch member 12 so that said member will be caused to move with the arbor. This 65 switch member is rotatably mounted on a hollow stub shaft 13 which is mounted in the insulation block 14 secured to the rear of the casing. This block is provided with recesses in its inner and outer faces to receive the switch parts. A split metal ring 15 forms the walls of the inner recess the split ends being considerably separated, as shown as 15' in Figure 6 and a projection 16 formed on the block projects into this 70 space and acts as a stop for the switch member 12. This member 12 carries a spring plunger 17, the spring of which holds the outer end thereof against the ring 15 to keep the same in electrical contact with said 75 ring 15 but this electrical connection is broken when the switch member reaches a position where the plunger will ride off the metal ring into the space 15' between its ends, when this plunger strikes the stop 16 further movement of the switch member and its attached parts will be prevented. This ring 15 is provided with an ear 18 which extends through the block into the recess in its rear face and engages the contact 19 80 which is adapted to be connected with one terminal of the electric circuit. A ratchet ring 20 is located in the rear recess of block 14 and is connected with the stub shaft 13 by having an inwardly extending projection 21 engaging the shaft and held thereto by the nut 22. This ring 20 is connected with the second contact 23 to which the second terminal of the electric circuit is adapted to be secured.

It will thus be seen that when the plunger 17 is in contact with ring 15 the circuit will be completed between the two contacts 19 and 23 through ring 15 and its ear 18, the switch member 12 and its plunger, the shaft 13 and the ring 20 and its part 21. As soon as the plunger enters the space 15', however, the circuit will be broken. Thus by rotating the arbor by disc 7 the spring plunger is moved into engagement with the ring 15 105 to complete the circuit and the further the plunger is moved away from space 15' the 110

longer the circuit will remain on. The extent of this movement of the parts is indicated by the finger moving over the dial so that a person can adjust the parts to keep the current flowing for a number of hours or fractions thereof. This setting movement will also wind the spring of the clock mechanism and as soon as the said movement ceases the spring acts to return the parts to place the finger at zero and to move the plunger off the ring.

I also provide means for manually making and breaking the circuit, such means consisting of a solid shaft 24 which passes through the arbor and the stub shaft 13 and disc 7 and has its front end screw threaded to engage the screw threaded bore of the finger disc 25. The rear end of said shaft carries a member 26 which is provided with a square part which passes through a square opening formed in a switch blade 27 which engages the ratchet teeth in ring 20 and is also adapted to engage the projecting part of contact 19. A spring 28 on the member 26 permits the switch blade to slide over the ratchet teeth. As will be seen when the blade is in engagement with the contact 19 the circuit between the contacts 19 and 23 will be completed as ratchet ring 20 is electrically connected with contact 23. Thus by manipulating disc 25 the circuit can be closed while the time switch is in off position.

The switch parts on the outer face of block 14 are covered by a second insulation block 14' which is secured to the first block and is provided with a central recess for receiving the member 26. The disc 25 acts to hold the disc 7 in position.

From the above it will be apparent that the time switch can be set so that it will break the circuit at some future time and the snap switch can be used for making and breaking the circuit when the time switch is in inoperative position.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A switch comprising a casing, an insulating block secured to the rear of said casing and being formed with inner and outer recesses, a hollow shaft passing through said casing and having one end arranged in the inner recess, a stub shaft arranged in the block and extending into said recesses, means of connection between the hollow shaft and stub shaft respectively, a ratchet ring arranged in the outer recess, a projection extending inwardly from the ratchet ring and securing the latter to the stub shaft, a solid shaft passing through the hollow shaft and stub shaft, a member having a square part secured to the solid shaft, a switch blade secured to the square part and resiliently retained engaged in the teeth of the ratchet ring, and a contact member arranged in the path of the switch blade which is movable upon rotation of the solid shaft.

2. A time switch comprising a casing, a dial on the front of said casing, an insulating block secured to the rear of said casing and being formed with a recess, a hollow shaft passing through said casing and extending into the recess, means in the casing for rotating said hollow shaft, an indicating finger on said hollow shaft and cooperating with said dial, a stub shaft in the insulating block, a switch member secured to the stub shaft and disposed in the recess, a ring secured to the hollow shaft and having projections received in notches formed in the switch member whereby the latter is rotated by the movement of the hollow shaft, a split ring engaged in the recess and having its ends spaced, a laterally disposed plunger secured to the switch member and being normally engaged with the split ring, a projection formed on the block and arranged in the space between the ends of the split ring and also in the path of the switch member to limit the rotation of the plunger when it leaves the split ring, and a setting disk on the hollow shaft for arranging the indicating finger and switch member simultaneously at predetermined points for the purpose specified.

In testimony whereof I affix my signature.

NICHOLAS FEINEN.
